E. KLEIN ET AL

COAT HANGER

Filed Oct. 22, 1921

UNITED STATES PATENT OFFICE.

EUGENE KLEIN, SAMUEL KLEIN, AND MORRIS KLEIN, OF SOUTH PASADENA,
CALIFORNIA.

COAT HANGER.

Application filed October 22, 1921. Serial No. 509,526.

To all whom it may concern:

Be it known that we, EUGENE KLEIN, SAMUEL KLEIN, and MORRIS KLEIN, citizens of the United States, and residents of South 5 Pasadena, in the county of Los Angeles and State of California, have invented new and useful Improvements in Coat Hangers, of which the following is a specification.

This invention relates to coat hangers, 10 and more particularly to a type of coat hanger adapted to be formed of light weight sheet material, such as paper, paper pulp, fibre or the like, and adapted to be molded into form suitable for receiving and holding 15 garments such as coats, vests, trousers, skirts and the like.

Another object is to provide in a coat hanger of the character mentioned, a coat hanger having a portion thereof arched in 20 the center and with inclined portions extending outwardly therefrom for receiving and holding a coat or the like, and a central portion connected with said coat receiving portion and provided with slides extensibly 25 supported thereon, whereby garments of greater width than the body of the hanger may be supported when not in use.

Other objects will appear as the description progresses.

30 We have illustrated two separate forms of our invention in the accompanying drawings, in which:

Fig. 1 is a side view of one form of our improved coat hanger, provided with extensible slides for accommodating the hanger to garments of different width.

Fig. 2 is a section of the same on line 2, 2 of Fig. 1.

Fig. 3 is an enlarged similar section of 40 the same, showing the details thereof.

Fig. 4 is a side elevation of a modified form of hanger; and Fig. 5 is a section thereof on line 5, 5, of Fig. 4.

Our improvements consists primarily and briefly, in a coat hanger formed of sheet material such as fabric, paper, fibre pulp or the like, including halved body portions molded into form and glued or otherwise suitably held together for use, thus providing a simple, economical, compact hanger of light weight and adapted for supporting different kinds of garments when not in use.

For instance, we may use sheets of paper such as old newspaper, wrapping paper,

fabric or other material by first applying a 55 coat of adhesive substance on the sides of each of the sheets and thereafter pressing several sheets together and molding the structure thus provided into a suitable form for carrying out the purposes of our invention. Thus, the hanger is built up of a plurality of laminations which may be readily molded into the desired form and reinforced by beads of ribs around the edges so as to prevent the bending or warping of the structure, and to lend rigidity and strength thereto.

Such a structure is shown in the drawings, and will be now described.

The preferred form of hanger is composed of a pair of substantially similar and mating body members B and B' built up of a plurality of laminations of sheet material, and molded into form. In the preferred form of structure shown, we provide a web 70 portion W for each of said body members, which has a semi-circular bead b around the upper edge thereof, and a similar but smaller bead b' extending across the lower portion thereof.

The meeting edges of the bead portions b and b' are overlapped as at 2, 2 in Fig. 3, and the web portions W, W are held in abutting position so as to form a web of double thickness between the bead portions b and b', and so that the said bead portions when the bends B and B' are attached together may be of substantially circular cross section, thus providing a reinforcement around the edge of the structure for lending rigidity 85 and strength thereto.

The larger bead b has a central arched portion a, with downwardly inclined portions 3, 3 extending therefrom to the ends e, e, and the lower bead b' has relatively 90 horizontal portions b¹, b¹, extending inwardly from the ends e, e, and connecting with an arched portion a' in the center. It will be noted that the arched portion a' is formed on a radius of substantially greater 95 length than the arched portion a in the center of the upper bead b.

In the center of the hanger we provide the usual form of hood H which has a stem h extending downwardly through the center of the upper bead b, and into the interior thereof, where it is provided with a head h' against which is held a metallic

strap C which has its ends C', C' extending through the opposite sides of the bead b and bent over the outer surfaces of said beads, as shown in Fig. 3.

5 The hook H is thus securely attached to the upper bead b of the structure, and the metal strap C serves in addition to strengthening the connection between the hook and the body of the hanger, to also attach the 10 two body parts B and B' together.

The portions b¹, b¹, are arranged to slidably receive a pair of slides S, S, which are of such cross section as shown in Fig. 3, as to correspond to the outer periphery of the 15 lower bead b', so that a gap will be provided between the edges of said slide to permit the movement of the slides over the web W of the hanger. These slides may be formed of the same material to correspond 20 to the material of the hanger, or they may be of metal or other suitable substances.

The length of the slides is such that when retracted to their innermost positions the outer ends e' thereof will be flush with or 25 inwardly of the ends e, e, of the hanger. The ends e, e, of the hanger however, are so formed that the slides S, S, will move readily thereover, and said slides may be extended outwardly from the ends of the 30 hanger for a substantial distance so as to accommodate the hanger for the purpose of supporting garments of greater width than the hanger, such as skirts and the like.

In the form of device shown in Figs. 4 35 and 5, we have provided a lower rib O which parallels the portions b¹, b¹, of the hanger, and an opening O' is provided be-

tween said portions so that trousers or other garments may be inserted through the opening O' of the hanger and held in position 40 on the member O. In this form of device the ends e, e, of the hanger are necessarily enlarged and are of somewhat different form, but the construction of the hanger is 45 substantially similar to the form shown in Fig. 1.

It will be seen from the foregoing description of our invention that we have provided an effective form of coat hanger which may be made of extremely light material and may be molded into such shape 50 as to provide ample rigidity and strength for all uses to which it may be put.

We may modify and alter the structure and form of our invention without departing from the spirit thereof or enlarging the 55 scope of the appended claim.

What we claim is:

A coat hanger composed of a plurality of 60 laminations of flexible material having their adjacent surfaces secured together and molded into form, so as to provide an upper bead portion, a central web portion, and a lower bead portion of integral formation, and slidable members carried on said lower 65 bead portion and adapted to be extended outwardly from the ends, for the purpose described.
